CLAIM

The ornamental design for a watch bezel as shown and described.

DESCRIPTION

The patent or application file contains at least one drawing executed in color. Copies of this patent or patent application publication with color drawing(s) will be provided by the Office upon request and payment of the necessary fee.

FIG. 1 is a front perspective view of a first embodiment of the watch bezel;

FIG. 2 is a top view thereof;

FIG. 3 is bottom view thereof;

FIG. 4 is a right-side thereof;

FIG. 5 is left-side thereof;

FIG. 6 is front view thereof; and

FIG. 7 is a rear view thereof;

FIG. 8 is a front perspective view of a second embodiment of the watch bezel;

FIG. 9 is a bottom view thereof;

FIG. 10 is a top view thereof;

FIG. 11 is a right-side thereof;

FIG. 12 is left-side thereof;

FIG. 13 is front view thereof; and,

FIG. 14 is a rear view thereof.

The features shown in broken lines form no part of the claimed design.
